(57) **CLAIM**

The ornamental design for video game console, as shown and described.

DESCRIPTION

FIG. 1 is a side perspective view of the video game console according to the invention, showing our new ornamental design;

FIG. 2 is a top plan view thereof;

FIG. 3 is a bottom plan view thereof;

FIG. 4 is a front elevational view thereof;

FIG. 5 is a back elevational view thereof;

FIG. 6 is a left side elevational view thereof; and,

FIG. 7 is a right side elevational view thereof.

The broken lines are for illustrative purpose only and form no part of the claimed design.
